ATTORNEY

UNITED STATES PATENT OFFICE.

FRANK BERNARDI, OF STOCKTON, CALIFORNIA.

SAD-IRON HEAT-REGULATOR.

1,199,729.

Specification of Letters Patent. Patented Sept. 26, 1916.

Application filed July 6, 1915. Serial No. 38,163.

To all whom it may concern:

Be it known that I, FRANK BERNARDI, a citizen of the United States, residing at Stockton, in the county of San Joaquin and 5 State of California, have invented new and useful Improvements in Sad-Iron Heat-Regulators, of which the following is a specification.

This invention relates to a mechanism 10 which is especially designed to regulate and control the temperature of electrically heated implements such as sad irons and the like.

It consists of a metallic support which is 15 expandible by the heat conveyed to it from the electrically heated iron which rests upon it, means to multiply the movement caused by the expansion and an automatic switch which is controlled by the expansion and the 20 multiplying means.

It also includes means by which any desired degree may be maintained by the operation of the switch actuating mechanism, and details of construction all of which will 25 be more fully described by reference to the accompanying drawings in which—

Figure 1 is a plan. Fig. 2 is a detail vertical longitudinal section on line 2—2 of Fig. 1. Fig. 3 is a detail vertical transverse 30 section on line 3—3 of Fig. 1.

It is desirable and necessary in order to produce good work that sad irons be heated to, and maintained at certain temperatures, and it is the object of this invention to determine such temperature, and to automatically regulate it within desired limits and thus prevent injury to the work to be done.

As shown in the drawings A is a base upon which may be fixed a fiber or asbestos sheet 40 2, and upon this is secured a metal frame 3. Upon this frame may be secured an asbestos sheet 4, which serves to support the metal expandible plate 5. This plate is bolted to the above support, at one end, while the opposite end is free to expand or contract, by variation of the heat applied to it.

An electrically heated iron 5^a is adapted to rest upon the plate 5 and the heat generated within the iron is communicated to the 50 plate and thus expands and extends it in the direction of its free end.

7 is a lever fulcrumed at 8, and having its short arm connected at 9 to the plate 5. The other arm of the lever is enough longer than 55 this first arm, to considerably increase the movement caused by the expansion of the

plate 5. By means of this lever and the following mechanism the heat control is effected.

Electric current is supplied from any suitable source to the binding posts 10 and thence through a suitable socket, and cord connection to the implement and its resistance coils, thus heating it. A main switch lever 11 serves to open or close the circuit.

12 is a conductor terminating in a guide 13 in which and a companion guide 13^a, a bar 14 is slidible. This bar carries at one end, a contact member 15 which abuts against the companion contact 16, as shown. 70 The other conductor 12^a connects the switch 11 with the point 16, and when the bar 14 is in contact with 16 the electric circuit is completed through these members and also through the iron 5^a.

The members 14 and 16 are normally held in contact by a spring 17 which exerts a constant pressure against the member 14. By means of a screw 18 the tension of this spring, and the consequent pressure of the 80 member 14 against 16 may be varied, or the circuit broken altogether. The bar 14 has an upturned part 19, through which passes a screw 20, the point of which may act against the outer movable end of the lever 7. 85 This screw is adjusted so that when the desired temperature of the implement has been reached, the expansion of the plate 5 acts through the lever 7, the outer end of which is thus moved until it contacts with the screw 90 20 and moves it and the bar 14 back, so as to disengage the latter from the member 16, and cut off the electric current through the implement. The screw 20 may be so adjusted as to determine the heat of the iron 95 by the temperature at which the points 14 and 16 are separated. The member 16 may preferably have a replaceable contact 16^a which may be renewed whenever worn out.

By means of this apparatus, I am enabled 100 to adjust and maintain the desired temperature with but little attention.

Various modifications in construction may be made without departing from the essential features of this invention.

Having thus described my invention, what I claim and desire to secure by Letters Patent is—

1. In combination with a support including a plate expandible and contractible in 110 response to temperature variations, an arm extending outwardly from the plate, a lever

5 pivoted at one end to the support and pivotally connected between its ends to said arm, a slideable spring tensioned contact carrying bar on the support, a stationary contact on the support for engagement with the bar contact, and an abutment on the bar for engagement with the opposite end of the lever.

2. In combination with a support including a member expansible and contractible in 10 response to temperature variations, a switch including a slideable contact, and a pivoted lever engageable with the sliding contact and connected to the member whereby upon heating of the member above a predetermined 15 point the lever will be moved to engage the switch and open the latter.

3. In a device of the type set forth, a base, insulating material thereon, an expansible

metal plate on said insulating material having one end rigidly secured to the base and 20 its opposite end free to expand or contract, a lever pivoted at one end to the base and pivotally connected between its ends to the plate, a stationary contact on the base, a slideable spring pressed contact on the base, 25 and a screw adjustably carried by the slideable contact and adapted to engage the other end of the lever.

In testimony whereof I have hereunto set my hand in the presence of two subscribing 30 witnesses.

FRANK BERNARDI.
